CONTROL SYSTEM INTERCONNECTING THE
OPERATION OF TWO MACHINES

In pending patent application Ser. No. 858,667 filed Sept. 17, 1969, now U.S. Pat. No. 3,579,690 there is disclosed a toe lasting machine, for wiping the toe portion of an upper margin against an insole, that includes a heel clamp for holding a shoe assembly in position during the wiping position. The heel clamp is movable from a remote position to a position of engagement with the heel of the shoe assembly. After performing the toe-wiping operation in a toe-lasting machine of this type, it is desirable to wipe the heel portion of the upper margin against the heel portion of the insole in a heel-lasting machine of the type disclosed in pending application Ser. No. 41,500 filed May 28, 1970. This heel-lasting machine includes a toe rest that supports the vamp of the upper during the heel wiping operation.

When succeeding shoe assemblies are of different length, it is necessary to adjust the position of the toe rest in the heel lasting machine so that the toe rest will be in the proper vamp-supporting position. This invention is concerned with a mechanism for enabling the operation of the toe-lasting machine on a particular shoe assembly to automatically adjust the position of the toe rest of the heel lasting machine for that shoe assembly. This is accomplished by modifying the two machines so as to provide a control mechanism so constructed that the distance between the location of engagement of the heel clamp with a shoe assembly in a particular machine cycle of the toe-lasting machine and the location of engagement of the heel clamp with a shoe assembly in a preceding machine cycle of the toe-lasting machine is effective to shift the toe rest an amount that is proportional to this distance in a direction that corresponds to the direction that extends from the location of engagement of the heel clamp with a shoe assembly in the receding machine towards the location of engagement of the heel clamp with a shoe assembly in the particular machine cycle.

Although the control system is disclosed as interrelating the operation of a toe-lasting machine and a heel-lasting machine, the invention in its broadest aspects is useful to interrelate the operation of any two machines, having workpiece engaging members, that successively operate on workpieces of different sizes.

In the drawings:

FIG. 1 is a side elevation of the toe lasting machine;

FIG. 2 is a front elevation of the upper portion of the toe-lasting machine;

FIG. 3 is a partially sectional side elevation of a portion of the toe lasting machine;

FIG. 4 is a plan view of the heel clamp of the toe-lasting machine;

FIG. 5 is a view taken on the line 5-5 of FIG. 4;

FIG. 6 is a view taken on the line 6-6 of FIG. 4;

FIG. 7 is a view of a portion of the control mechanism taken on the line 7-7 of FIG. 1;

FIG. 8 is a partially sectional side elevation of a portion of the control mechanism;

FIG. 9 is a view taken on the line 9-9 of FIG. 8;

FIG. 10 is a view taken on the line 10-10 of FIG. 8;

FIG. 11 is a side elevation of the heel-lasting machine;

FIG. 12 is a front elevation of the heel lasting machine taken on the line 12-12 of FIG. 11;

FIG. 13 is a side elevation of a portion of the heel lasting machine;

FIG. 14 is a view taken on the line 14-14 of FIG. 13;

FIG. 15 is a schematic representation of a pneumatic circuit of the control system;

FIG. 16 is a schematic representation of an electric circuit of the control system;

FIG. 17 is a representation of a shoe assembly as it appears in the toe-lasting machine just before the toe wiping operation;

FIG. 18 is a view taken on the line 18-18 of FIG. 17;

FIG. 19 is a representation of a shoe assembly as it appears in the heel-lasting machine at the beginning of a machine cycle of the heel-lasting machine;

FIG. 20 is a view taken on the line 20-20 of FIG. 19;

FIG. 21 is a representation of a shoe assembly as it appears in the heel-lasting machine just before the heel-wiping operation; and

FIG. 22 is a view taken on the line 22-22 of FIG. 21.

The toe-lasting machine 10 is shown in FIGS. 1-6. The operator is intended to be located to the left of the machine as seen in FIG. 1, and a direction extending towards the operator (right to left in FIG. 1) will be referred to as "forward" while a direction extending away from the operator (left to right in FIG. 1) will be referred to as "rearward."

The toe-lasting machine 10, as shown in FIG. 2, has mounted therein a toe insole rest 12, a pair of forepart rest 14 and an applicator-support 16. As seen in FIGS. 2 and 3, a plate 18 is mounted in a head 20 that forms a part of the machine frame. A pair of toe wipers 22 are mounted in wiper cams 24 that are slidably supported on a thickened block 26 that forms the front of the plate 18. An air-actuated motor 28, secured to a flange 30 on the back of the plate 18, is operatively connected to the toe wipers 22 so as to effect movement of the toe wipers in a toe-wiping stroke.

Referring to FIGS. 1-3, an air-actuated motor 32 is secured to a hanger 34 depending from the head 20. The piston rod 36 of the motor 32 is connected by way of a plate 38 to a pair of bars 40 that are slidably guided in bosses 42 and 44 affixed to the machine frame. A yoke 46 is secured to and straddles the front ends of the bars 40. A post 48 is mounted to the yoke 46.

Referring to FIGS. 4-6, a carrier 50 is mounted to a mount 52 that is secured to the top of the post 48. A heel clamp holder 54 is pivotally mounted to the carrier 50 by means of a pin 56. A heel clamp 58 is mounted to the holder 54 for swinging movement about a heightwise axis by means of pivot pins 60. The heel clamp is formed of two rearwardly divergent mount portions 62 and 64. A clamp pad 68 is rigidly secured to the portion 62. A clamp pad 68 is pivotally connected, by a hinge 70, to the top of the portion 64 and extends downwardly and rearwardly of a back flange 72 on the portion 64. A spring return air-operated actuating valve 74 is mounted to the flange 72. The valve stem 76 of the valve 74 is urged rearwardly, by the conventional spring in the valve 74, through a hole 78 in the flange 72 to bear against the clamp pad 68 and urge the clamp pad 68 rearwardly about the hinge 70 away from the flange 72.

Referring to FIGS. 1 and 7-10, a rack 80 is secured to and extends rearwardly of the yoke 46. The rack 88 is in mesh with a pinion 82. The pinion 82 is pinned to a shaft 83. The top of the shaft 83 is pinned to a knob 85 that is located above the pinion 82. The shaft 83 extends through a shelf 87 of the frame of the machine 10 and is pinned to a sleeve 89.

A shaft 84, located below the shaft 83, is pinned to a collar 91. A pin 93, secured to the bottom of the shaft 83, is slideable in a slot 95 formed in the collar 91. A compression spring 97, interposed between the shelf 87 and the sleeve 89 acts to yieldably urge the sleeve 89, together with the shaft 83 downwardly to a position herein the sleeve 89 is bearing against the top of the collar 91, the pin 93 is at the bottom of the slot 95, and the pinion 82 is in mesh with the rack 80. The shaft 84 is connected by shafting 86 to a shaft 88 in such a manner that rotation of the pinion 82 causes rotation of the shaft 88. The shaft 88, which has a gear 90 affixed thereto, is rotatably mounted in a housing 92.

A piston 94 is mounted for heightwise movement in a cylinder 96 that is secured to the housing 92. A pin 98, secured to the cylinder 96, extends through a slot 100 in the piston 94 to limit the extent of heightwise movement of the piston in the cylinder. A rod 102, secured to the piston 94, extends upwardly of the cylinder 96 through a boss 104 that forms a part of the frame 92. Pressurized air entering the cylinder 96 below the piston 94 through a line 106 acts to raise the piston 94 and the rod 102 to the extent permitted by

pin 98 and the slot 100. When the air in the line 106 is vented, a compression spring 108, extending about the rod 102 and interposed between the piston 94 and a sleeve 110 that is fixed to the boss 104, acts to lower the piston 94 and the rod 102 to the extent permitted by the pin 98 and the slot 100.

The rod 102 extends through a hub 112 and the center of a gear 114 that are secured to each other and are rotatable about the rod 102. A clip 116, that is secured to the boss 104, extends into a groove 118 in the hub 112 to restrain the hub and the gear 114 against heightwise movement. The gear 114 is in mesh with the gear 90. A cam 120 is secured to the top of the gear 114. As shown in FIG. 10, the periphery of the cam is defined by a curved segment 122 that is concentric with and of slightly smaller radius than the periphery of the gear 114 and a sloped chordal segment 124. The chordal segment 124 is so offset from the axes of the rod 102 and the gear 114 that the cam 120 is somewhat less than semicircular.

Above the gear 114, the rod 102 extends through a gear 126 that is rotatable about the rod. A cap 128 is rotatably mounted to the top of the rod 102 above the gear 126. Prongs 130, secured to the cap 128, extend downwardly into and are slidably received by holes 132 extending through the gear 126. Electric switches 134 and 136 are mounted to the opposite ends of the cap 128. The actuators for the switches 134 and 136 extend downwardly through slots in the gear 126. Rollers 138 and 140 are respectively secured to the actuators for the switches 134 and 136.

A reversible electric motor 142 is mounted to the housing 92 and is operative to rotate a gear 144. The gear 144 is in mesh with a gear 146. A shaft 148 is pinned to the gear 146 and is rotatably mounted in the housing 92. A screw 150 is secured to the shaft 148 for rotation in unison therewith. The screw 150 is threaded into a bracket 152 that is slidably mounted in the housing 92 for forward-rearward movement by means of gibs 154. The top of the bracket 152 is secured, by means of a spacer 156, to a rack 158. The rack 158 is in mesh with the gear 126.

The heel-lasting machine 160, which is located alongside the toe-lasting machine 10, is shown in FIGS. 11-14. In operating this machine, the operator stands to the left of the machine as seen in FIG. 11, and a direction extending towards the operator (right to left in FIG. 11) will be referred to as forward while a direction extending away from the operator (left to right in FIG. 11) will be referred to as rearward.

The machine 160 comprises a post 162, mounted for heightwise movement, whose upper end is received in a recess in a platform 164 and is secured to the platform by a pin 166. A base 168 is slidably mounted on the platform 164 for forward-rearward movement. A screw 170, rotatably mounted in the platform 164, is threadedly received in a hanger 172 that depends from the base 168. The screw is connected to a sprocket 174 that is rotatable in a flange 176 that is secured to the front of the platform 164. A sprocket 178, also rotatably mounted in the flange 176, is connected to the sprocket 174 by a chain 180. The sprocket 178 is connected to a reversible electric motor 182 that is also mounted to the flange 176. Thus it can be seen that the base 168 and the parts carried thereby may be adjusted forwardly and rearwardly in the platform 164 by the motor 182.

Referring to FIGS. 13 and 14, a column 184 is mounted to and extends upwardly of the base 168. An air-actuated motor 186 is mounted to the column 184. The piston rod 188 of the motor 186 is secured to a bar 190 that is mounted for heightwise movement in the column 184. A beam 192 is secured to the top of the bar 190 and extends laterally of the bar on opposite sides thereof. A block 194 is slidably mounted on each end of the beam 192 for inward-outward movement. A link 196 is pivoted at its outer end to each block 194. The inner end of each link 196 is pivoted by a pin 198 to the periphery of a hub 200 that is secured to a gear 202. The hub 200 and the gear 202 are rotatably mounted on the bar 190, and the pins 198 are mounted to diametrically opposed portions of the periphery of the hub 200. A block 204 is slidably

mounted on each block 194 for inward-outward movement. Oppositely threaded screws 206 are rotatably mounted to flanges 208 that are secured to the blocks 194. The screws 206 are threaded into the blocks 204. A square shaft 210 is secured to one of the screws 206 and is slidably received in a square hole in the other screw 206. A mount 212 is secured to and extends upwardly of each block 204. Valves 214 and 216 are secured to the mounts 212. Gauges 218 and 220, pivotally mounted to the brackets 212, are located in alignment with the valve stems 222 of the valves 214 and 216. A rack 224, secured to the platform 164, is in mesh with a gear 226. The gear 226 is secured to a shaft 228 that is rotatably mounted in the column 184. A gear 230, that is secured to the top of the shaft 228, is in mesh with the gear 202.

A rod 232 is slidably mounted in the bar 190 for heightwise movement and extends through an opening in the beam 192. The top of the rod 232 is secured to a mount 234. Pins 236 extend downwardly from the mount 234 into openings in the beam 192 to guide the mount for heightwise movement. A compression spring 238 extends between the top of the bar 190 and the mount 234 to yieldably urge the mount upwardly. A pin 240, secured to the bar 190 extends into a groove 242 in the rod 232 to prevent the bar from twisting about its axis. The engagement of the pin 240 with the bottom of the groove 242 limits the extent that the spring 238 can urge the mount 234 upwardly. A valve 244, that is secured to the bar 190, has an upwardly extending valve stem 246 that is in alignment with the bottom of the rod 232. A toe rest 248 is movably mounted in the mount 234 for lateral movement by means of rolls 250 that are rotatably mounted to the toe rest and are received in gibs 252 that are secured to the mount 234.

A lever 254 is pivoted intermediate its ends to the column 184. The upper end of this lever has a brake pad 256 secured thereto that is movable toward and away from the bar 190. The lower end of this lever is in alignment with the piston rod 258 of an air operated spring return motor 260 that is mounted to the column 184.

Referring to FIG. 13, a base 262 is secured to the platform 164 rearwardly of the column 184. A column 264 is mounted to the base 262 for lateral movement by means of gibs 266 on the column that are slidable in the base. An air-actuated motor 168 is mounted on a flange 270 that is secured to the base 262. The piston rod 271 (FIG. 12) of the motor 268 is secured to the column 264 whereby the motor effects lateral movement of the column.

A mount 272 is mounted to the column 264. A bracket 274, secured to the top of the mount 272, pivotally supports a spindle 276 by a laterally extending pin 278. A last support plate 280 is pivotally mounted on the forward-rearward axis of the spindle 276 and a last pin 282 is secured to and extends upwardly of the plate 280. Due to the ability of the spindle 276 to swing about the axis of the pin 288 and the plate 280 to swing about the axis of the spindle 276, the plate 280 and the pin 282 are flexibly mounted to the mount 272 so as to be capable of having limited universal movement with respect to the mount 272.

Referring to FIG. 11 and 12, a head 284 is located rearwardly of the mount 272. A pair of wiper cams 286 are movably mounted between plates 288 and 290 that form parts of the head 284. Heel wipers 292 are mounted to the wiper cams 286.

In the idle condition of the toe-lasting machine 10: the motor 28 retains the toe wipers 22 in a retracted position; the piston rod 36 is projected out of the motor 32 so that the heel clamp 58 is in a forward position; pressurized air is entering the cylinder 96 through the line 106 to raise the piston 94; and the switches 134 and 136 are open.

Referring to FIGS. 17 and 18, a shoe assembly to be toe lasted is presented bottom-down to the machine 10. The shoe assembly comprises a shoe insole 294 located on the bottom of a last 296, as by being tacked thereto, and a shoe upper 298 draped about the last.

The shoe assembly is placed in the machine 10 and this machine is operated in such manner that the shoe is supported by the insole rests 12 and 14 and the applicator-support 16 as indicated in FIGS. 17 and 18, and a quantity of cement has been extruded through holes 300 and a groove 302 (FIGS. 2, 17 and 18) in the applicator-support 16 against the bottom of the margin of the toe portion of the insole. At this time, as indicated in FIGS. 17 and 18, the toe wipers 22 are located in a retracted position and the shoe assembly is at such a level that the bottom of the toe portion of the insole 294 is above the level of the tops of the wipers 22 an amount that is approximately equal to the thickness of the margin of the upper 298, a holdown 304 is bearing against the top of the forepart of the shoe assembly and a yoke 306 is bearing against the toe portion of the upper 298.

Now, the motor 32 is actuated to move the heel clamp 58 rearwardly until the clamp pads 66 and 68 engage the heel end of the shoe assembly. At this time, teeth 308 (FIG. 4) in the holder 54 are in locking engagement with toothed wings 310 on the heel clamp 58 to lock the heel clamp in such a position about the axis of the pins 60 that both clamp pads 66 and 68 are tangential to the sides of the shoe assembly when they engage it. The engagement of the clamp pad 68 with the shoe assembly causes this clamp pad to swing about the hinge 70 against the flange 72 (FIG. 6) to thereby shift the valve stem 76 to open the valve 74. The opening of the valve 74 operates a motor 312 (FIG. 3) to apply brakes 314 against the bars 40 to lock the heel clamp 58 in the position it had assumed when engaging the heel end of the shoe assembly.

Prior to operating the toe-lasting machine 10, the operator had raised the knob 85 (FIG. 7) to raise the pinion 82 out of mesh with the rack 80 and had rotated the knob to thereby rotate the shafts 83, 84 and 88 and the gears 90 and 114 so as to rotate the cam 120, which acts as a setting member, to the solid line initial position of FIG. 10 wherein the rollers 138 and 140 are offset from the chordal segment 124 of the cam 120.

The rearward movement of the heel clamp 58, by means of the rack 80, the pinion 82, the shafts 84 and 86 and the gears 90 and 114, causes the cam 120 to rotate counterclockwise (FIG. 10) from the initial position shown in solid lines in FIG. 10 wherein the rollers 138 and 140 are offset from the cam 120 to the setting position indicated in phantom in FIG. 10 wherein a portion of the cam 120 has moved beneath the roller 140. The angle extending between the roller 140 and the chordal segment 124 of the cam 120 when the heel clamp has engaged the heel end of the shoe assembly is dependent on and proportional to the length of the shoe assembly.

Referring to FIG. 15, pressurized air enters the cylinder 96 to raise the piston 94 from a source 314 through a line 316, a valve 318 and the line 106. The opening of the valve 74, in response to engagement of the clamp pad 68 with the heel of the shoe assembly, enables pressurized air to pass from the source 314 through a line 320, the valve 74 and a pilot line 322 to the valve 318 to shift the valve 318. The shifting of the valve 318 cuts off the flow of pressurized air to the cylinder 96 and enables the air in the cylinder 96 to vent to atmosphere through the line 106 and the valve 318. As a result, the spring 108 moves the rod 102 downwardly to lower the roller 140 into engagement with the cam 120 and thereby close the switch 136.

Referring to FIG. 16, wherein lines 324 and 326 are connected to a source of electric power, the closure of the switch 136 operates the motor 142 to rotate the screw 150 in such a direction as to move the bracket 152 and the rack 158 leftwardly (FIG. 8) to thereby rotate the gear 126, together with the prongs 130, the cap 128, and the switches 134, 136 counterclockwise (FIG. 10) until the roller 140 has passed the cam chordal segment 124, shown in phantom in FIG. 10, so that both rollers 138 and 140 are offset from the cam 120 as shown in phantom in FIG. 10. The arrival of the rollers 138 and 140 to this position causes the switch 136 to open while the switch 134 remains open.

The closure of the switch 136 also operates the motor 182 to rotate the screw 170 in such a direction as to move the hanger 172, the column 184 and the toe rest 148 rightwardly (FIG. 13) to bring the toe rest 248 closer to the plate 280 and the last pin 282. When the switch 136 is opened due to the arrival of the roller 140 in the position shown in phantom in FIG. 10, the motor 182 is turned off and the toe rest 248 ceases its movement.

10 The opening of the valve 74 also causes the yoke 306 to be forced against the shoe assembly under a heavier clamping pressure than had heretofore been applied and also causes bumpers 328 (FIGS. 2 and 18) to be forced against the foreparts of the upper in regions that are rearward of the yoke 306. At this time the parts assume the position shown in FIGS. 17 and 18.

15 Now the motor 28 is operated to move the wipers 22 forwardly and inwardly in a wiping stroke to wipe the toe portion of the margin of the upper 298 against the insole 294 and bond the upper margin to the insole by means of the cement that had been extruded against the insole. As the wipers 22 perform their wiping stroke the applicator-support 16 and the insole rests 12, 14 are lowered out of the path of the oncoming wipers so that the shoe assembly is supported on its bottom solely by the wipers, thus enabling the holdown 304 to press the shoe assembly directly against the wipers and provide an overwiping pressure. Towards the end of the wiping stroke, the holdown 304 is forced downwardly under heavier bedding pressure for predetermined length of time to iron the now wiped toe portion of the upper margin against the insole and to enable the cement that is between the wiped upper margin and the insole to bond the upper margin to the insole. At the end of this predetermined length of time, the machine parts are returned to their idle conditions to complete the 20 machine cycle.

25 The return of the heel clamp 58 to its idle position causes the rack 80 to swing the cam 120 clockwise (FIG. 10) back to the solid line position shown in FIG. 10. The rollers 138, 140, together with the switches 134, 136 remain in the phantom 30 position shown in FIG. 10.

35 If the next shoe assembly to be operated on by the toe lasting machine 10 is of the same length as the shoe assembly operated on in the first cycle described above, the cam 120 will swing counterclockwise (FIG. 10), pursuant to the movement of the heel clamp 58 against the heel of the shoe assembly, through the same angle as in the first cycle. Therefore, when the switches 134 and 136 are lowered by the rod 102, both of the rollers 138 and 140 will be laterally offset from the cam 102 and both of the switches 134 and 136 will remain open. As a result, the motors 142 and 182 will not be operated and the position of the toe rest 248 will not change.

40 If the next shoe assembly to be operated on by the toe lasting machine 10 is longer than the shoe assembly operated on in the first machine cycle, the cam 120 will swing counterclockwise through a smaller angle than in the first machine cycle. Therefore, when the switches 134 and 136 are lowered by the rod 102, the roller 138 will engage the cam 120 to close the switch 134 while the switch 136 remains open. Referring to FIG. 16, the closure of the switch 134 operates the motor 142 to rotate the screw 150 in such a direction as to move the bracket 152 and the rack 158 rightwardly (FIG. 8) to thereby rotate the gear 126 and the switches 134, 136 clockwise (FIG. 10) until the roller 138 has passed the cam chordal segment 124 so that both the rollers 138 and 140 are offset from the cam 120 and the switch 134 is opened. The closure of the switch 134 also operates the motor 182 to rotate the screw 170 in such a direction as to move the hanger 172 leftwardly (FIG. 13) to move the toe rest 248 further from the plate 280 and the last pin 282.

45 The next shoe assembly to be operated on by the toe-lasting machine is shorter than the shoe assembly operated on in the first machine cycle, the cam 120 will swing counterclockwise through a greater angle than in the first machine cycle. Therefore, when the switches 134 and 136 are lowered by

the rod 102, the roller 140 will engage the cam 120 to close the switch 136 while the switch 134 remains open. The closure of the switch 136 operates the motor 142 to move the bracket 152 and the rack 158 leftwardly (FIG. 8) to thereby rotate the gear 126 and the notches 134, 136 counterclockwise (FIG. 10) until the roller 140 has passed the cam chordal segment 124 so that both the rollers 138 and 140 are offset from the cam 120 and the switch 136 is opened. The closure of the switch 136 also operates the motor 182 to rotate the screw 170 in such a direction as to move the hanger 172 rightwardly (FIG. 13) to move the toe rest 248 closer to the plate 280 and the last pin 282.

From the foregoing, it can be seen that the spacing of the toe rest 248 with respect to the plate 280 and the last pin 282 in the heel-lasting machine 160 is at all times proportional to the length of the shoe assembly that is being operated on by the toe-lasting machine 10.

In the idle condition of the heel-lasting machine 160: the post 162 and the parts supported by the post 162, including the gauges 218, 220, the toe rest 248, the plate 280 and the last pin 282, are in a lower position; the piston rod 188 is retracted into the motor 186 so that the gauges 218, 220 and the toe rest 248 are in a lower position with respect to the column 184; the piston rod 258 is retracted into the motor 260 so that the brake pad 256 is not in pressing engagement with the bar 190; no pressurized air is entering the motor 168 so that the column 264 is movable along the gibs 266; and the wipers 292 are in a retracted position.

Referring to FIGS. 19 and 20, a shoe assembly, after having been toe lasted in the toe-lasting machine 10, is placed bottom-up on the last support constituted by the last pin 282 and the plate 280 with the last pin 282 entering the thimble hole 330 of the last and the plate 280 bearing against and supporting the top of the heel portion of the last. The shoe assembly and the plate 280 are swung counterclockwise (FIG. 19) so as to cause the top of the vamp of the upper to bear against the toe rest 248. The toe rest 248 is properly spaced from the last pin 282, in accordance with the length of the shoe assembly, to receive the vamp of the upper due to its having been moved toward or away from the last pin 282 by the motor 182 during the toe-lasting operation as described above.

Depending on whether a shoe assembly for a left foot or a right foot is being operated on, the operator swings the shoe assembly counterclockwise or clockwise (FIG. 20) about the support plate 280 and the last pin 282 with the top of the vamp of the shoe assembly moving the toe rest 248 laterally along the mount 334 until the side of the toe rest engages the gauge 218 or the gauge 220. In response to the engagement of the shoe assembly with one of the gauges 218 and 220, the valve 214 or 216 causes the motor 268 to be actuated to shift the column 264 together with the plate 280 and the last pin 282 laterally in such direction and to such an extent as to cause the heel periphery of the shoe assembly to lie on the line of symmetry of the heel wipers 292. The gauges 218 and 220 are so located that, after this lateral shifting, the heel periphery of the shoe assembly bears a desired symmetrical relationship with respect to the leading edges of the heel wipers 292. When operating on a shoe assembly of a different length, the motor 182 moves the base 168 together with the column 184, the gauges 218 and 220 and the toe rest 248 to change the spacing between the toe rest 248 and the plate 280 and the last pin 282. During this movement, the gear 224 moves along the rack 226 to cause the shaft 228 to rotate in one direction or the other thereby causing the gear 202 to rotate so as to cause the links 196 to move the gauges 218, 220 inwardly or outwardly. The links 196 are so constructed that the movement of the toe rest 248 further from the last pin causes the gauges 218, 220 to move outwardly and the movement of the toe rest closer to the last pin causes the gauges to move inwardly. Therefore, the operation of the motor 182 to adjust the spacing of the toe rest with respect to the last pin for a different length of shoe also acts to change the spacing between the gauges 218, 220 for this different length of shoe.

Now holdown feet 332 and 333 FIGS. 11, 12, 21 and 22 are moved to a position wherein their bottoms lie in a plane that is slightly below the plane formed by the bottoms of the heel wipers 292. This is followed by a raising of the post 162 and the parts carried thereby, including the last pin 282, the plate 280 and the toe rest 248 until the insole 294 bears against the holdown feet 332, 333. The flexible mounting of the pin 282 and the plate 280 to the mount 272 enables the pin 282 and the plate 280 to move with respect to the mount 272 during this rise until the heel seat portion 334 (FIGS. 21 and 22) of the insole bears flushly against the holdown feet 332, 333 to thereby level the insole heel seat against the holdown feet and locate it in a plane parallel to and slightly below the plane of the bottoms of the heel wipers 292. During the rise of the shoe assembly, the operator may let go of the shoe assembly, the shoe assembly staying proximate to the gauge 218 or 220 due to inertia and being locked in this position at the end of the rise due to being clamped between the plate 280 and the holdown feet 332, 333. The leveling of the insole heel seat 334 against the holdown 332, 333 causes the top of the vamp of the upper to rise upwardly of the toe rest 248, the extent of this rise being dependent on the style of the shoe.

During the rise of the post 162, the motor 186 is actuated to raise its piston rod 188 together with the bar 190 and the toe rest 248. The engagement of the toe rest 248 with the top of the vamp of the upper, during the rise of the toe rest, causes the rod 232 to open the valve 244. The opening of the valve 244 causes the motor 260 to be actuated to press the brake pad 256 against the bar 190 and thus lock the toe rest 248 against movement.

Now a pad 336 (FIG. 12) is caused to firmly engage the shoe assembly and clamp the heel portion of the upper 298 against the last 296, as shown in FIGS. 21 and 22, with the heel portion 338 of the upper margin extending upwardly of the insole heel seat portion 334.

At this time, cement is sprayed radially from a nozzle 340 (FIG. 22) on the upper margin 338 and/or the periphery of the insole heel seat portion 334. This is followed by a forward and inward movement of the wipers 292 in a wiping stroke so as to wipe the upper margin 338 against the insole heel seat 334 and bond the upper margin to the insole by means of the sprayed cement.

During the wiping operation, the holdown feet 332, 333 are raised out of the way of the wipers 292, and, at the end of the wiping stroke, the post 162 is moved upwardly under heavier pressure than had heretofore been applied bedding pressure between the wiped upper margin and the bottoms of the wipers. After the bedding pressure has been applied for a predetermined length of time, the machine cycle of the heel lasting machine 160 is completed, the machine parts are returned to their idle positions and the shoe assembly is released.

I claim:

1. A control system interrelating the operation of two machines comprising: a first machine operable to perform a first operation on a workpiece during each machine cycle; a second machine operable to perform a second operation on a workpiece; a first workpiece-engaging member in the first machine; means movably mounting the first workpiece-engaging member so as to enable it to engage a workpiece during a machine cycle in a location that is dependent on the size of the workpiece; a second workpiece-engaging member in the second machine that is adapted to be engaged by a workpiece during the performance of the second operation; means movably mounting the second workpiece-engaging member in the second machine; and a control mechanism interconnecting the machines operable to cause the second workpiece engaging member to move an amount that is proportional to the distance between the location of engagement of the first workpiece engaging member with a particular workpiece during a particular machine cycle and the location of engagement of the first workpiece engaging member with a different workpiece during the machine cycle that precedes said particular

machine cycle and in a direction that corresponds to the direction extending from the location of engagement of the first workpiece engaging member with said different workpiece towards the location of engagement of the first workpiece engaging member with said particular workpiece.

2. A control system according to claim 1 wherein the control mechanism further comprises: an actuating member mounted to the first workpiece engaging member; means responsive to the engagement of the first workpiece engaging member with a workpiece to actuate the actuating member; and means responsive to the actuation of the actuating member to operate the control mechanism.

3. A control system according to claim 1 further comprising: means mounting the first work-engaging member for movement from a starting location toward the workpiece and means effective during a machine cycle to yieldably move the first workpiece-engaging member from the starting location towards a workpiece to thereby enable the first workpiece engaging member to move an amount that is dependent on the size of the workpiece; and wherein the control mechanism comprises: a setting member; means mounting the setting member for movement from an initial position; means so connecting the first workpiece-engaging member and the setting member as to move the setting member from its initial position to a setting position by an amount that is proportional to the distance between the starting location and the location of engagement with a workpiece of the first-workpiece engaging member; and a shifting mechanism for causing the second workpiece engaging member to move by an amount that is proportional to the distance between the setting position during said particular machine cycle and the setting position during said preceding machine cycle and in a direction that corresponds to the direction extending from the setting position in said particular machine cycle and the setting position in said preceding machine cycle.

4. A control system according to claim 3 wherein the control mechanism further comprises: an actuating member mounted to the first workpiece engaging member; means responsive to the engagement of the first workpiece-engaging member with a workpiece to actuate the actuating member; and means responsive to the actuation of the actuating member to operate the shifting mechanism.

5. A control system for interrelating the operation of a toe-lasting machine and a heel-lasting machine; wherein the toe lasting machine comprises: means for supporting a shoe assembly that includes a last having an insole on its bottom and an upper draped thereon with the toe end of the shoe assembly facing rearwardly; toe wiping means movable in a toe wiping stroke to wipe the toe portion of the margin of the upper against the insole; a heel clamp located forwardly of the shoe assembly; and means mounting the heel clamp for rearward movement as to enable it to engage a shoe assembly during a machine cycle in a location that is dependent on the length of the shoe assembly to hold the shoe assembly in position during

a toe wiping stroke; wherein the heel-lasting machine comprises: a support for supporting a shoe assembly with the heel of the shoe assembly facing rearwardly; heel wiping means movable in a heel-wiping stroke to wipe the heel portion of the margin of the upper against the insole; and a toe rest, located forwardly of the support and mounted for forward-rearward movement, adapted to support the vamp of a shoe assembly during a heel wiping stroke; and further comprising: a control mechanism interconnecting the machines operable to cause

5 the toe rest to move an amount that is proportional to the distance between the location of engagement of the heel clamp with a particular shoe assembly during a particular machine cycle and the location of engagement of the heel clamp with a different shoe assembly during the machine cycle that precedes said particular machine cycle and in a direction that corresponds to the direction extending from the location of engagement of the heel clamp with said different shoe assembly towards the location of engagement of the heel clamp with said particular shoe assembly.

10 6. A control system according to claim 5 wherein the control mechanism comprises: an actuating member mounted to the heel clamp; means responsive to the engagement of the heel clamp with a shoe assembly to actuate the actuating member; and means responsive to the actuation of the actuating member to operate the control mechanism.

15 7. A control system according to claim 5 wherein the toe-lasting machine further comprises: means mounting the heel clamp for movement from a starting location toward the shoe assembly; and means effective during a machine cycle to yieldably move the heel clamp from the starting location towards a shoe assembly to thereby enable the heel clamp to move an amount that is dependent on the length of the shoe assembly; and wherein the control mechanisms comprises: a setting member; means mounting the setting member for movement from an initial position; means so connecting the heel clamp and the setting member as to move the setting member from its initial position to a setting position by an amount that is proportional to the distance between the starting location and the location of engagement with a shoe assembly of the heel clamp; and a shifting mechanism for causing the toe rest to move an amount that is proportional to the distance between the setting position during said particular machine cycle and the setting position during said preceding machine cycle and in a direction that corresponds to the direction extending from the setting position in said particular machine cycle and the setting position in said preceding machine cycle.

20 8. A control system according to claim 7 wherein the control mechanism further comprises: an actuating member mounted to the heel clamp means responsive to the engagement of the heel clamp with a shoe assembly to the actuating member; and means responsive to the actuation of the actuating member to operate the shifting mechanism.

UNITED STATES PATENT OFFICE
CERTIFICATE OF CORRECTION

PATENT NO. : 3,628,207

DATED : December 21, 1971

INVENTOR(S) : Jacob S. Kamborian

It is certified that error appears in the above-identified patent and that said Letters Patent are hereby corrected as shown below:

Column 10: lines 12 and 14, change "show" to --shoe--; line 33, change "mechanisms" "to --mechanism--; delete line 43; line 51, insert a semi-colon after "clamp"; line 52, after "to" insert --actuate the--.
